Des. 197,138
Patented Dec. 17, 1963

197,138

HOLDER FOR COCKTAIL OLIVES OR THE LIKE

James H. Ogg, North Hollywood, Calif., assignor to Zoo-Piks, North Hollywood, Calif., a partnership

Filed July 24, 1963, Ser. No. 75,943

Term of patent 14 years

(Cl. D44—29)

FIG. 1

I claim:

The ornamental design for a holder for cocktail olives or the like, substantially as shown.
